UNITED STATES PATENT OFFICE.

JOHN A. THAYER, OF CAMBRIDGEPORT, MASSACHUSETTS.

IMPROVEMENT IN HATCHETS.

Specification forming part of Letters Patent No. 170,972, dated December 14, 1875; application filed May 11, 1875.

To all whom it may concern:

Be it known that I, JOHN A. THAYER, of Cambridgeport, of the county of Middlesex and State of Massachusetts, have invented a new and useful Improvement in Hatchets; and do hereby declare that the same to be fully described in the following specification, and represented in the accompanying drawings, of which—

Figure 1 is a top view, Fig. 2 a side elevation, Fig. 3 an edge view, and Fig. 4 a perspective view, of it.

The said implement has an eye to receive a handle. It also has not only a hatchet-blade and hammer-head but a curved claw and adz blade or scraper, all being arranged as represented, and usually cast in one solid piece of steel.

In such drawings, A denotes the handle-eye, which is tubular or socketed to receive a handle, B, arranged therewith, as shown. From one side of the said eye a hatchet-blade, C, extends, a hammer-head, D, being projected from the eye in the opposite direction. There also extends from the eye, transversely to the hatchet-blade and hammer-head, not only a curved claw, E, such as in hammers

is used for drawing a nail out of an article, but an adz cutter or scraper, F, all being as shown in the drawings.

The tool or implement, composed of the handle-eye, hatchet-blade, hammer-head, claw, and adz-cutter, arranged and combined together and with a handle, as described, is a very convenient one for use in boxing or barreling merchandise or other matters, it saving the necessity of having separate cutting-tools for driving or extracting nails, or for erasing marks or preparing surfaces for receiving letters or marks.

If preferable, the adz-cutter may be disposed in range with the hatchet-blade, and the hammer-head be disposed in range with the claw; but it is evident that either of such arrangements of the parts would not be so useful as that exhibited in the drawings.

I claim—

As my invention the implement, as described and represented.

JOHN A. THAYER.
